GEORGE E. PELLISSIER, OF JERSEY CITY, NEW JERSEY, ASSIGNEE TO LOUIS D. PELLISSIER, OF HOLYOKE, MASSACHUSETTS.

ADJUSTABLE RAIL-GRINDER.

1,031,959.

Specification of Letters Patent.

Patented July 9, 1912.

Original application filed January 19, 1911, Serial No. 603,526. Divided and this application filed December 21, 1911. Serial No. 667,115.

To all whom it may concern:

Be it known that I, GEORGE E. PELLISSIER, a citizen of the United States, and a resident of the city of Jersey City, county of Hudson, and State of New Jersey, have invented 5 certain new and useful Improvements in Adjustable Rail-Grinders, set forth in the following specification.

This invention relates to certain improvements in rail grinders and more particularly to that type which embodies a grinding member so mounted that it may be moved along the rail forming a portion of the track and remove surface irregularities therein.

15 One of the objects of my invention is to provide an adjustment of the grinding member permitting of its being readily and conveniently adapted to remove different kinds of surface irregularities or unevennesses in 20 different kinds of rails.

A further and special object is to provide 25 an adjustment permitting of the removal of sharp depressions in the rail, as at so-called "pounded joints," by forming a long shallow depression merging into the straight portions of the rail surface.

30 A further object is to better control the movement of the grinding member along the track while the grinding operation is taking place, but by a simple adjustment permit the vehicle carrying the grinding member to be attached to a hand-car or other draft means and moved along the track at greater speed with the grinding member out of operation.

35 Other objects and advantages of my improved construction will be set forth herein-after and particularly pointed out in the claims.

Figure 1 is a top plan view of a rail 40 grinder constructed in accordance with my invention, a portion thereof being broken away and a portion being shown on the line 1-1 of Fig. 3; Fig. 2 is a vertical longitudinal section on the line 2-2 of Fig. 1; Fig. 45 3 is a transverse vertical section, the power means for one of the grinding members being removed; Fig. 4 is an enlarged face view of the wheel shown at the left end view of Fig. 2, the axle being adjusted to eccentric 50 position; Fig. 5 is a sectional view of the wheel shown in Fig. 4; and Figs. 6, 7, and 8 are diagrammatic views illustrating different

positions assumed by the grinder during the operation of removing a sharp dip or depression in the rail.

55

In the specific form of my invention here illustrated, I mount the grinding members, which are preferably emery-wheels, upon a truck having a main frame 10 formed of channel iron. Adjacent opposite ends of the 60 frame are bearings for the axles 11 and 12, and upon these axles are pairs of wheels 13 and 14 mounted to travel along the rails forming the track. Extending across the frame intermediate the ends thereof is a 65 cross-rail 15 serving as a support for the grinding members. This cross-rail is illustrated as being rigidly secured in place at a point somewhat nearer the axle 11 than the axle 12, but it is evident that the cross- 70 rail might be secured in place at any point along the length of the frame of the truck and might be so mounted as to facilitate its adjustment from one position to another. Mounted upon this cross-rail or guide are 75 two saddles or slides 16 so constructed as to be retained in engagement with the cross-rail, but being adjustable along the length thereof in a direction transversely of the track. Preferably these saddles have removable flanges 17 for retaining them in position and by the removal of which the saddles may be taken off the cross-rail. Extending lengthwise of the rail are two screw rods 18 provided with handles 19 at their 80 outer ends and having threaded engagement with projections 20 on the saddles so that by turning the handles the saddles may be drawn along the cross-rail to any position desired.

85

90

95

Mounted upon each saddle or horizontally movable slide 16 is a bracket or vertically movable slide 21. These brackets may be retained in engagement with the saddles in any suitable manner, but preferably by means of a dove-tailed guide and guideway as shown in the upper portion of Fig. 1. Vertically disposed within each bracket is a screw rod 22 having a handle 23 at its upper end and having threaded engagement 100 with the projection 24 on the saddle so that by turning the handle 23 the bracket may be raised or lowered. This raising or lowering of the bracket is independent and unaffected

ed by the lateral movement of the saddle. Each bracket has depending arms carrying a shaft 25 to one end of which is secured a grinding member 26 which, as hereinbefore stated, is preferably in the form of an emery wheel. This emery wheel is of any shape or contour desired, dependent upon the shape and character of the rail to be ground and the nature of the irregularities to be removed. At the left-hand side of Fig. 3 I have shown one form of emery wheel for grinding one type of rail and at the right-hand side I have shown a somewhat different wheel for grinding an ordinary T-rail. Each bracket 21 carries a motor 27, here shown as an electric motor, which preferably is detachably and adjustably connected to the bracket by suitable fastening means, such as the bolts 27' engaging the bracket through elongated slots 27' therein. From said motor power is transmitted to the shaft 25 in any suitable manner, as for instance, by a belt 28. By the mechanism above described the emery wheels may be adjusted vertically or laterally to any desired position relatively to the rails to be ground and when in this position the truck or vehicle bearing the grinding members may be moved in engagement with the rails so as to grind the latter in a desired manner.

For propelling the vehicle, I preferably provide one of the axles, for instance, the axle 11, with one or more worm wheels 29 adapted to mesh with a worm 30 mounted on a shaft 31 extending upwardly to a point above the platform supported by the main frame. Said shaft preferably extends through a sleeve 32 which is pivotally mounted at 32' beneath the platform. With the shaft extending in the position indicated in Fig. 2 the worm is in engagement with the worm wheel and the vehicle may be slowly advanced by turning the handle 31' at the upper end of the shaft. When it is desired to advance the vehicle at a greater rate of speed with the grinding member out of operation the shaft 31 may be swung about the pivot 32' so that its axis will occupy the position diagrammatically indicated and the worm will be out of mesh with the worm wheel. Any suitable locking device may be employed for holding the shaft in either of its limiting positions. The platform is preferably provided with a slot through which the shaft may move, and pivoted dogs 33 are mounted at the ends of the slots and movable into position within the slot to prevent the swinging movement of the shaft. In certain forms of my improved device I may mount an electric motor 50 on the platform and drive the car at the desired slow rate of speed by this motor 50, releasably to the supporting wheels 13 in any suitable manner as by gearing 51, 52

and clutch 53, so as drive the worm shaft 31.

In order to grind out sharp depressions or so-called "pounded joints", I preferably so mount the wheels at one end of the main frame that their axle may be brought to an eccentric position. By having the axle eccentric, the frame and therefor the supported emery wheels may be caused to gradually lower and raise during the advancement of the grinder through a predetermined distance dependent upon the circumference of the eccentric wheels. As shown in Figs. 2, 4 and 5, the wheels 14 are bored to a considerably larger diameter than the axles, and within the bored out hub is placed a bushing 34. This bushing constitutes a mounting for the wheel upon the axle and has the passage therethrough disposed somewhat off center. The bored passage through the wheel is also off center preferably the same amount as is the passage through the bushing 34 off center so that in rotating the bushing in respect to the wheel the axle may be brought to the true center of the wheel or is shown provided for fixing said wheel to said bushing in various positions of relative rotation to adjust the degree of eccentricity between said wheel and its axis. As shown, each bushing has a flange 35 disposed adjacent one surface of the wheel and provided with a plurality of notches 36 about the periphery thereof. A slide 37, having a key projection 37' for engagement with the flange 35 within its said notches, is adjustably connected to the wheel by screws 38 so that when it is moved into engagement with the flange 35 it will lock the wheel and bushing against relative rotation. Access to these adjusting means from the platform of the car may be conveniently had through an opening 39 in said platform which is normally closed by a swinging door 40.

Normally the axle 12 is at the center of the wheel 14 so that the wheels and grinding members move substantially parallel and the emery wheels grind the track smooth and straight. When it is desired to grind out a depression in the track, however, the wheels 14 are brought to an eccentric position, the eccentricity depending upon the depth to which it is desired to grind the rails at the joint. In Figs. 6, 7 and 8, I have shown the parts somewhat diagrammatically and adjusted for grinding out a depression, the depression and eccentricity adjustment being shown exaggerated to render the disclosure more clear. Starting with the parts in the position shown in Fig. 6 and slowly advancing the grinder, the emery wheel 26 will gradually lower as the grinder advances until the lowest point of the main depression is reached, as shown in Fig. 7, and then will gradually rise, grinding to less and less

depth, until finally the elongated and now shallow depression, indicated by dotted lines, merges into the normal surface of the rail, as shown in Fig. 8. After a depression in 5 a rail is ground out in the manner described, the wheels 14 may be readjusted so as to be concentric with their axle and the grinder may then proceed along the track removing such irregularities as may occur.

10 This application is a division and continuation of my co-pending application, Serial No. 603,526, filed Jan. 19, 1911 for rail grinder.

What is claimed and what is desired to 15 be secured by United States Letters Patent is:

1. In combination, a rail grinder comprising a movable carriage; propelling mechanism for said carriage; a grinding 20 tool carried by said carriage; and automatically operating means adapted to move said grinding tool vertically to the operating surface, said automatically operating means comprising an eccentric member itself 25 adjustable so as to impart a predetermined amount of movement to said grinding tool.

2. In combination, a rail grinder comprising a movable carriage; a traction wheel for said carriage; means for driving 30 said traction wheel; an idler wheel spaced from said traction wheel; an operating tool intermediate said wheels; and means coöperating with one of said wheels adapted to move said operating tool vertically to the 35 operating surface.

3. In combination, a rail grinder comprising a movable carriage; a traction wheel for said carriage; means for driving 40 said traction wheel; an idler wheel spaced from said traction wheel; an operating tool intermediate said wheels; and means operating in unison with the rotation of said traction wheel adapted to move said operating tool vertically to the operating surface.

4. In combination, a rail grinder comprising a movable carriage; a traction wheel adjacent one end of said carriage; means 45 for driving said traction wheel; an idler wheel adjacent the opposite end of said carriage; an operating tool carried by said carriage intermediate said wheels; and means operating in unison with the rotation of said traction wheel adapted to incline the frame of said carriage for moving said operating tool vertically to the operating surface.

5. In combination, a rail grinder comprising a movable carriage; a traction wheel 50 for said carriage; means for driving said traction wheel; an idler wheel spaced from said traction wheel; an operating tool intermediate said wheels; and means operating in unison with the rotation of said traction 55 wheel adapted to move said operating tool

vertically to the operating surface; and independent means for adjusting said operating tool relatively to said carriage.

6. In combination, a rail grinder comprising a movable carriage; a traction wheel for said carriage; means for driving said traction wheel; an idler wheel spaced from said traction wheel; a transverse guideway carried by said carriage intermediate said wheels; an operating tool movable along 75 said guideway; and means operating in unison with the rotation of said traction wheel adapted to move said guideway vertically to the operating surface for elevating or depressing said operating tool relative to the 80 operating surface.

7. In combination, a rail grinder comprising a movable carriage; propelling mechanism for said carriage; an operating tool carried by said carriage; and means operated by said propelling mechanism adapted to move said operating tool vertically to the operating surface.

8. In combination, a rail grinder comprising a movable carriage; propelling mechanism for said carriage; an operating tool carried by said carriage; and means operated by said propelling mechanism adapted to move said operating tool vertically to the operating surface in accordance with a 90 predetermined changing ratio relative to the movement of said carriage.

9. In a surface grinder, a traveling carriage; means for guiding said carriage along the work; power driven means for propelling said carriage; an adjustable head plate mounted movable on said carriage; a rotary operating tool mounted on said head plate; a separate motor mounted on said head plate and mechanically connected with 100 said tool whereby said motor and tool may be adjusted as a unit relatively to the work; and means operating in unison with the movement of said carriage along the work for adjusting said carriage vertically relatively to the working surface.

10. In combination, a rail grinder comprising a traveling carriage; means for guiding said carriage along the rail; an adjustable head plate mounted movably on 115 said carriage; a vertical guideway for said head plate; means for moving said head plate along said guideway; a rotary operating tool mounted on said head plate; a separate motor mounted on said head plate and mechanically connected with said tool whereby said motor and tool may be adjusted as a unit vertically relatively to the rail; and independent means operating in unison with the movement of said carriage along the 120 rail for bodily elevating and depressing said carriage to move said operating tool vertically to the operating surface.

11. In combination, a rail grinder comprising a traveling carriage; means for 125

- guiding said carriage along the rail; an adjustable head plate mounted movably on said carriage; a guide frame for said head plate comprising a vertical guideway; a cross guideway for said guide frame; means for moving said frame along said cross-guideway; a rotary operating tool mounted on said head plate; a separate motor mounted on said head plate and mechanically connected with said tool whereby said motor and tool may be adjusted as a unit relatively to the rail; and independent means operating in proportion to the movement of said carriage along the rail for bodily elevating and depressing said cross guideway to move said operating tool vertically to the operating surface.
12. In a surface grinder, a traveling carriage; means for guiding said carriage relatively to the work; a head plate adjustably mounted on said carriage; a rotary operating tool and a separate motor therefor both mounted on said head plate; means for propelling said carriage; and means operated by said propelling means for automatically imparting a gradual movement to said operating tool vertically to the operating surface.
13. In a surface grinder, a traveling carriage; means for guiding said carriage relatively to the work; an operating tool movable with the carriage adapted to be moved vertically relative to the work; and automatically operated means for imparting said vertical movement to said operating tool at a predetermined gradually changing ratio relatively to the advancement of said carriage along the work, for reducing sharp irregularities to gradual irregularities so that said gradual irregularities will be curvied from beginning to end.
14. In a surface grinder, a support; an operating tool mounted on said support adapted to be moved along the work; and means for automatically adjusting said tool vertically to the work at a predetermined gradually changing ratio relatively to the advancement of said tool along the work, for reducing sharp irregularities to gradual irregularities so that said gradual irregularities will be curvied from beginning to end.
15. In a surface grinder, a traveling carriage; means for guiding said carriage relatively to the work; a head plate adjustably mounted on said carriage; a rotary operating tool and a separate motor therefor both mounted on said head plate; said head plate, with said motor and tool, being adapted to be adjusted automatically at a predetermined gradually changing ratio relatively to the advancement of said carriage along the work, for reducing sharp irregularities to gradual irregularities so that said gradual irregularities will be curvied from beginning to end.
16. In a rail grinder, the combination comprising a carriage movable along a rail; a traction wheel for driving said carriage; an idler wheel spaced from said traction wheel; an operating tool mounted on said carriage adapted to operate upon said rail as said carriage is moved along said rail; and means for driving said traction wheel, said means being readily disconnected from driving relation with said traction wheel for leaving said carriage free to be towed along the track.
17. In a rail grinder, the combination comprising a carriage movable along a rail; a traction wheel for driving said carriage; an idler wheel spaced from said traction wheel; an operating tool mounted on said carriage adapted to operate upon said rail as said carriage is moved along said rail; automatically operating means for adjusting said operating tool vertically to the rail at a predetermined gradually changing ratio relative to the advancement of said carriage along the rail; and adjustable means for effecting non-operation of said automatically operating means.
18. In a rail grinder, the combination comprising a carriage movable along a rail; a traction wheel for driving said carriage; an idler wheel spaced from said traction wheel; an operating tool mounted on said carriage adapted to operate upon said rail as said carriage is moved along said rail; automatically operating means for adjusting said operating tool vertically to the rail at a predetermined gradually changing ratio relative to the advancement of said carriage along the rail; and means for driving said traction wheel, said means being readily disconnected from driving relation with said traction wheel for leaving said carriage free to be towed along the track.
19. In a rail grinder, the combination comprising a carriage movable along a rail; a traction wheel for driving said carriage; an idler wheel spaced from said traction wheel; an operating tool mounted on said carriage adapted to operate upon said rail as said carriage is moved along said rail; automatically operating means for adjusting said operating tool vertically to the rail at a predetermined gradually changing ratio relative to the advancement of said carriage along the rail; means for driving said traction wheel; adjustable means for effecting non-operation of said automatically operating means; and means for disconnecting said traction wheel driving means from driving relation with said traction wheel, all whereby said carriage may be left free to be towed along the track.
20. In a rail grinder, the combination comprising a carriage wheel movable along a rail; a traction wheel for driving said carriage; an idler wheel spaced from said

traction wheel; an operating tool mounted on said carriage adapted to operate upon said rail as said carriage is moved along said rail; power means for driving said traction wheel; hand operating means for driving said traction wheel; and selective means for placing into operative relation either of said driving means.

21. A rail grinder including a grinding member; means for moving said grinding member along a rail; and means for imparting automatically a gradual movement at right angles to said rail to said grinding member simultaneously with its movement along the rail and at predetermined relative rates, so as to grind sharp irregularities into gradual irregularities.

22. In combination, a rail grinder comprising a movable carriage; a cross rail mounted upon the frame of said carriage, a

grinding member movably attached to said cross rail; means for gradually raising and lowering said grinding member relatively to said cross rail; means for gradually moving said grinding member along said cross rail; means for gradually propelling said movable carriage along the rails to be ground; means for readily disconnecting said propelling means so that the machine may roll freely along the track; and means for automatically raising and lowering to a desired degree one end of said movable carriage as it moves along the track.

In witness whereof, I have signed my name to this specification, in the presence of two subscribing witnesses.

GEORGE E. PELLISSIER.
